UNITED STATES PATENT OFFICE.

RICHARD W. JONES, OF SYRACUSE, NEW YORK.

HAME-CLIP STAPLE AND TUG-IRON.

SPECIFICATION forming part of Letters Patent No. 338,751, dated March 30, 1886.

Application filed January 28, 1886. Serial No. 190,036. (No model.)

To all whom it may concern:

Be it known that I, RICHARD W. JONES, a citizen of the United States, residing at Syracuse, in the county of Onondaga, State of New York, have invented certain new and useful Improvements in Hame-Clip Staples and Tug-Irons, of which the following is a specification, reference being had therein to the accompanying drawings, in which—

10 Figure 1 is a perspective view of a portion of a hame with my improvement applied thereto. Fig. 2 is a similar view with the tug-iron removed. Fig. 3 is a perspective view of the clip or staple portion of the device with the breast-ring attached. Fig. 4 is a longitudinal section of the same with the holdback-ring removed, and Fig. 5 is a view of one of the eyes of the clip.

My invention consists of a hame-clip staple 20 and tug-iron, so constructed that the tug-iron may be readily attached to or detached from the hame when turned in an abnormal relation to each other, and also in a split eye for the staple, as will be described.

25 In the drawings, A represents a portion of a hame of ordinary construction, having the usual link, a, at its lower end to receive the fastening-strap, or any other well-known and preferred form of fastening.

30 That portion of the device which is to take the place of the usual hame-staple consists, essentially, of three parts, two of which, B B, approximate the form of the ordinary screw-eye, and the third, C, consists of a pivoted bar with 35 a central annular portion, and having a short shaft or pintle at each side thereof, and these parts will now be particularly described. The eyes B B are preferably slightly frusto-conical exteriorly; but their interior portions, which 40 form bearings for the short shafts of the part C, are straight or of uniform diameter, as shown at b' b'. They are provided with shanks b² b², to go through the hame transversely, and may be either plain or cylindrical, so as to be up- 45 set on the back of the hame, to secure them in place; or they may be screw-threaded and secured to the hame simply by screwing them into the wood of the hame. The lower of these pieces B is provided with an eye, b³, in which 50 the holdback-ring C' is secured. The part C, as before stated, consists of a central annular portion, c', and on each side thereof are the

short shafts or pintles c² c², which, after being passed through their bearings in the eyes B B, may be headed, as shown at c³ c³. The annular part c' is substantially frusto-conical, although this is not essential, having on its under side a small peripheral projection, in which is located a groove or depression, c⁴, for a purpose to be hereinafter explained. This is one mode of construction; but I prefer to split the eyes B, as shown in Fig. 5. The part C is formed in this instance with the heads complete, and after the shafts or shanks of the part C are inserted they are closed thereon.

The tug or draw iron D, as shown, is provided with a head or enlarged portion, d', on the end of it, which engages with the clip. This portion of the tug-iron is substantially cylindrical, and is of such diameter that it will 65 turn freely in the socket in the annular portion C. The iron D is provided near its front end with a spline or feather, d², which fits the groove or recess in the part C; and it will be observed that while the spline is on the 70 front of the iron D its corresponding groove is in the back of the part C, or that part thereof which is nearest the face of the hame. The rear end of the iron D is flattened, as shown at D', and is provided with holes for its attachment to the tug by rivets or otherwise. The flattened portion D' is wider than the 75 diameter of the main bore or opening through the part C, but of substantially the width of its diameter across it at the point where the 80 groove or recess c⁴ is located, so that by turning the flat end in line therewith it may be readily inserted therein. After the flattened end of the iron D is passed through the part C it is turned about a quarter of a revolution, or 85 until the spline d² coincides with the groove c⁴, when it is again turned until the spline d² is in front, and it cannot be removed as long as it is in its working position. It will be 90 seen that the spline or feather d² does not extend to the head on the iron D, but that a cylindrical portion is left between the end of said spline and its head about the width of the part C, so that it may be turned freely vertically. It will also be apparent that it has free lateral 95 motion by virtue of the pivotal connection of the part C to the eyes B B. I also sometimes construct one of these eyes with a plate projecting sidewise from its shoulder and per-

forate it to receive the other eye, the plate in this instance lying upon the hame and provided with an eye projection to receive the holdback-ring.

5 By my invention I construct a hame in which the tug or draft is readily detached from the clip. The hames also draw straight backward without twist, and the irons being bent over clear of the collar prevent wear thereon.

10 Having thus fully described my improvement, what I claim as new, and desire to secure by Letters Patent, is—

1. A hame-clip staple and swiveled tug or draft iron constructed substantially as described, and made detachable from each other when brought into an abnormal relation, as set forth.

2. A hame-clip staple consisting of suitable eyes carrying a pivoted bar between them, provided with a grooved or recessed eye, in combination with a tug or draft iron, substantially as described.

3. A hame-clip staple provided with a pivoted bar having an annular socket or bearing provided with a groove or recess, in combination with a curved headed tug-iron flattened at one end, cylindrical at the other, and having a spline or feather thereon, substantially as set forth. 25

4. A hame-clip staple consisting of suitable eyes and a pivoted bar between them, in combination with a swiveled tug or draft iron, substantially as described. 30

5. In a hame-clip staple, the eyes split vertically and adapted to form bearings for the pivoted bar of the staple when closed, substantially as described. 35

In testimony whereof I affix my signature in presence of two witnesses.

RICHARD W. JONES.
